UNITED STATES PATENT OFFICE.

FREDERIC BARR, OF NEW YORK, N. Y.

ELECTRIC SWITCH.

1,097,208.

Specification of Letters Patent. Patented May 19, 1914.

Application filed December 12, 1912. Serial No. 736,306.

To all whom it may concern:

Be it known that I, FREDERIC BARR a citizen of the United States of America, and residing at New York, in the county of Kings 5 and State of New York, have invented new and useful Improvements in Electric Switches, of which the following is a specification.

My invention relates particularly to what 10 are commonly termed pull switches and the two forms herein shown are specially applicable to what are commonly termed lamp clusters.

One object is to provide a simple form 15 and arrangement of pull switch mechanism and supporting base which can be economically manufactured and readily assembled or disassembled and yet in which the parts are properly insulated and protected from 20 each other so that there is no likelihood of short circuiting or grounding.

Briefly considered, the invention contemplates an insulating base having a recess in its upper surface to receive the insulating 25 block carrying the pull switch mechanism. The contacts for the lamps are secured to the base. One of the circuit terminals is secured to the insulating base and the other is secured to the insulating block. The contacts for the lamps are surrounded by a 30 shell lined with insulation which in conjunction with the insulating base and the insulating block form an inclosing chamber for the switch mechanism. The operating cord 35 or chain as it is customarily called passes through insulating members which form an insulating passage.

Figure 1, is a vertical section of one form 40 of mechanism embodying my invention, the section being taken on the plane of the line X X of Fig. 2. Fig. 2, is a plan view of the same. Fig. 3, is an inside view of the insulating block and the switch contacts carried thereby. Fig. 4, is a plan view of 45 the same. Fig. 5, is a vertical section of another form of my invention, the section being taken on the plane of the line Y Y of Fig. 6. Fig. 6, is a plan view of the same. Fig. 7, is a detail view of the rotatable 50 switch member. Fig. 8, is a detail view of the rotating carrier of the switch member. Fig. 9, is a detail view of the operating ratchet member.

The base 1 is formed of porcelain or 55 other suitable insulating material such as fiber, etc. The screw socket contacts 2 for

the lamps (not shown) are carried by a frame 3 which is secured to the base for instance, by screws such as 4, 4 and 4'. The center lamp contacts such as 5, 5 are carried by a frame 6 which is secured to the insulating base for instance by means of screws such as 7, 7 and 7'.

The insulating base is provided with a recess to receive the insulating block 8 which 60 carries the switch contacts 9 and 10 and the brackets 11 and 12. The brackets and contacts are secured to the insulating block for instance by means of screws 13 and 14. The brackets are provided with wings 15 and 16 65 bent at right angles to and laterally to the switch contacts. One is provided with a binding screw 17 which thus in conjunction with it forms one of the circuit terminals. The other binding screw 18 is screwed into 70 a plate 19 which in conjunction with it forms the other circuit terminal which is secured to the insulating base 1 by means of the screw 7'. The bracket 12 and its wing 16 and thus the insulating block 8 are secured to the insulating base by means of the screw 4'.

The two-armed switch member 20 is mounted in one face of the rotary insulating carrier 21 on the spindle 22 which is rigidly 85 secured to the insulating block 8. The ratchet member 23 is also mounted on the spindle 22 and pressed toward the carrier 21 by a spring 24 which bears against the nut 25 screwed on to the outer end of the spindle. The switch contacts 9 and 10 are arranged inclined as the segments of an annular ring and have the inclined insulating steps 26 and 27 between them. The spring 24 not only presses the ratchet 23 against 90 the carrier 21 and thus presses the switch member contact against the switch contacts 9 and 10 and the inclined faces 26 and 27 but it also tends to rotate the ratchet member 23 clockwise so that the ratchet member 23 engages the shoulder 28 of the insulating block which acts as a back stop. The operating cord or chain 29 is secured to the ratchet member 23 in a suitable manner to adapt it to pull down the ratchet 23 and 100 thus rotate the switch member anti-clockwise. The upper part of the insulating block 8 is provided with a flange 30 which extends over the spindle, the switch contacts and the operating members and closes the 105 opening in the insulating base. A guard flange 31 is also provided around the lower

edge of the insulating block 8 to keep the chain away from the switch contacts. I also provide one or more insulating members, tubes or bushings such as 32, 33 and 34 to form an insulating guide passage for the operating chain. The member 32 is secured to the center lamp contact frame 6. The member 33 is secured to the contact frame 3 and the member 34 is secured to the shell 35 which has an insulating lining 36 which encloses and insulates all the interior mechanism. The electric circuit may be traced from the binding screw 18 through the plate 19, screw 7' into the center lamp contact frame 6 and from the binding screw 17, wing 15 and terminal bracket 11, contact 9, switch member 20, contact 10, bracket 12, wing 16 and screw 4' to the lamp screw socket bracket 3. The insulating base is preferably recessed to receive the circuit terminals as is shown in Fig. 2, while the insulating block 8 and its flange 30 fill the central opening and cover the switch mechanism.

In the form shown in Figs. 5 and 6 the insulating block 40 carries the bracket 41 for the screw lamp screw shells 42, the bracket being secured to the base by screws 43. One of these screws also secures the circuit terminal plate 44. The center ring 45 secured to the insulating base has center contacts 46 for the lamps. The switch mechanism proper is carried by an insulating block which fills the opening or recess in the insulating base 40. The spindle 47 is supported between the side flanges 48 and 49 and covered by the top flange 50. One switch contact 51 is connected by a screw 52 to the circuit terminal 53. The other switch contact 54 is secured by a screw 55 to a member 56 which passes down through the center ring 45 and is held in place by a nut 57. The electric circuit may be traced from the circuit terminal 44 through the screw 43 to the bracket 41 and lamp screw shell contacts 42, and from the circuit terminal 53 through the screw 52, switch contact 51, rotatable switch member (as shown in Fig. 7), switch contact 54, screw 55 and member 56 to the center ring 45 and its center contacts 46. In this construction the guide passage for the chain is formed by the insulating flange 58, insulating ring 59 and insulating tube 60, and all the parts are inclosed between the insulating base 40 and the casing or shell 61.

What I claim is:—

1. In an electric switch, an insulating base having a central recess opening on its upper face, an insulating block removably fitting in said recess and provided with an insulating flange closing the recess when the block is seated therein, pull switch mechanism carried by said block beneath the said insulating flange, lamp contacts carried by

said insulating base, a casing surrounding said lamp contacts and having a central passage and insulating members forming an insulating guide passage for the pull chain and insulating said chain respectively from 70 said lamp contacts and said casing.

2. In an electric switch, an insulating base having a central recess opening on its upper face, an insulating block removably fitting in said recess, pull switch mechanism carried by said block, lamp contacts carried by said insulating base, a casing surrounding said lamp contacts and having a central passage and insulating members forming an insulating guide passage for the pull chain and insulating said chain respectively from 75 said lamp contacts and said casing, a circuit terminal carried by said insulating block and a second circuit terminal carried by said insulating base.

3. In an electric switch, an insulating base having a central recess opening at its upper face, an insulating block removably fitting in said recess, pull switch mechanism carried by said block, lamp contacts carried by 90 said insulating base, a casing surrounding said lamp contacts and having a central chain passage, said block having an insulating flange over said switch mechanism and closing the upper part of said recess and a 95 chain guided in said central passage.

4. In an electric switch, an insulating base having a central recess opening at its upper face, an insulating block removably fitting in said recess, pull switch mechanism carried 100 by said block, lamp contacts carried by said insulating base, a casing surrounding said lamp contacts and having a central chain passage, a circuit terminal carried by said insulating block and a second circuit terminal carried by 105 said insulating base.

5. In a pull switch, a receptacle open at the top and having an insulated chain guide passage at the bottom, an insulating block fitting in said receptacle, switch mechanism 110 carried by said block, provided with outstanding brackets, one of said brackets forming a circuit terminal, lamp contacts in the receptacle, means connecting one of said lamp contacts with the other one of said outstanding brackets and the other of said lamp contacts provided with a second circuit terminal, a pull chain extending through said passage, said block closing the top opening in said receptacle.

6. In a pull switch, a receptacle having a recess at the top and having a central chain guide at the bottom, an insulating block removably secured in said recess, lamp contact frames in the receptacle and switch 125 mechanism carried by said block and including switch contacts, brackets diverging from said switch contacts, a circuit terminal screw in one bracket at the upper end of said receptacle, a screw connecting the other 130

bracket with one lamp contact frame and a second circuit terminal screw carried by said receptacle and connected with the other lamp contact frame.

- 5 7. In a pull switch, an insulating base having a recess, an insulating block fitting said recess, switch mechanism carried by said block and including contacts, a central chain guide at the bottom of said base, a
10 chain connected to said switch mechanism and depending through said chain guide and insulating guard flanges projecting from said block between said guide and said contacts.
- 15 8. In a pull switch, an insulating base hav-

ing a recess, lamp contacts carried by said base, an insulating block removably fitting the recess in the base, switch mechanism carried by the block, provided with outstanding brackets, one of said brackets forming a circuit terminal, means detachably connecting the other bracket with one of the lamp terminals on the base, a chain guide and a pull chain connected with the switch mechanism and extending through said chain guide. 20

FREDERIC BARR.
